EDMUND A. PARKER, OF MERIDEN, CONNECTICUT, ASSIGNOR OF ONE-HALF TO JAMES W. DAVIS AND ONE-SIXTH TO CHARLES H. COX, OF MERIDEN, CONNECTICUT.

COASTER AND BOTTLE-OPENER.

937,850.

Specification of Letters Patent.

Patented Oct. 26, 1909.

Application filed August 19, 1908. Serial No. 513,644.

To all whom it may concern:

Be it known that I, EDMUND A. PARKER, a citizen of the United States, residing at Meriden, county of New Haven, State of Connecticut, have invented an Improvement in Coasters and Bottle-Openers, of which the following is a specification.

This invention has for its object to provide a metallic coaster which shall be neat and attractive in appearance, practically unbreakable under the ordinary conditions of use, inexpensive to produce and so formed as to adapt it for use as a bottle opener, that is for removing crown stoppers from bottles in which lager beer, ginger ale and the various soft drinks are placed for retailing.

It is of course well understood that it is common in dispensing beverages, whether served upon hard wood tables or upon a tablecloth, to provide trays or coasters upon which the bottles are placed after being opened. These trays or coasters have been variously made of metal, wood, glass and earthenware and of combinations of these materials but without regard to the material have never been provided, so far as I am aware, with means, forming part of the coaster itself, which adapted it to serve additionally as a bottle opener or stopper remover.

It is of course well understood that bottle openers are easily lost and are frequently not to be found when wanted. Coasters, on the other hand, are not liable to get lost and each coaster, by my present invention, is also made a bottle opener.

In order to accomplish the desired result I have devised the novel combined coaster and bottle opener which I will now describe, referring to the accompanying drawing forming a part of this specification and using reference characters to indicate the several parts.

Figure 1 is an elevation showing the coaster in use with a bottle thereon, the stopper not having been removed; Fig. 2 a plan view of an all-metal coaster; Fig. 3 a view partly in section and partly in elevation illustrating the use of the device as a bottle opener; and Fig. 4 is a cross section on a larger scale illustrating a form of combined coaster and bottle opener in which the central portion of the bottom is made of some ornamental material as pressed or cut glass or earthenware.

10 denotes my novel coaster as a whole, the essential features of which are a bottom 11, a side flange 12 and an inwardly curved opening flange 13 which is formed integral with the side flange. The opening flange is shown as curved over inward and downward so that any portion of the edge thereof will form a catch, as at 13 in Fig. 3, to engage under the edge of a crown stopper. This flange also adds greatly to the strength of 60 the device as a whole. The device is preferably additionally strengthened by forming an inwardly projecting curved rib 14 in the bottom thereof. When used as a bottle opener this rib serves as a rest or fulcrum 70 which rests upon the top of the stopper and, when the edge of the opening flange is engaged with the edge of a stopper and pressure is applied to the outer edge of the bottom, pries the stopper upward and disengages it from the neck of the bottle, the leverage being so great that any stopper may be removed no matter how tightly it may have been set in place.

15 denotes a bottle and 16 a crown stopper 80 thereon.

In the form illustrated in Fig. 4, in the operation of forming, the central portion of the disk of metal is removed and an ornamental center, indicated by 17, is secured in 85 the opening. This ornamental center may be secured in place in any ordinary or preferred manner. For example, a circular rib 18 may be pressed inward from the metal forming the inner side of rib 14 against 90 which the edge of the upper side of the ornamental center may rest. The center is then securely locked in place by closing a flange of the metal under it as at 19, the center being clamped between rib 18 and the 95 flange, as is clearly shown in Fig. 4.

The operation will be readily understood from the drawing. In performing its ordinary function as a coaster, the device rests upon its bottom on a table or other suitable 100 support and carries the bottle, as in Fig. 1, the side and opening flanges preventing possible overflow or drip from the bottle getting upon the table and wetting the table or cloth. To remove a stopper, the device is inverted, the edge of the opening flange is caught under the edge of the stopper with the fulcrum rib or rest bearing upon the top of the stopper. Pressure is then applied to the outer edge of the bottom and the stopper 105 110

is instantly pried loose from the neck of the bottle and may be thrown off by the device without touching the stopper with the hand and without the slightest danger of injuring the hand of the operator.

In practice, when used as an opener the device is not likely to slip off as the opening flange engages the edge of the stopper firmly, but even if it should slip off no possible 10 injury to the operator can result.

Having thus described my invention I claim:

1. A combined coaster and bottle opener comprising a circular body provided with a 15 side flange the edge of which is turned over to form an opening lip, said body being provided with an annular depression forming a fulcrum rib.

2. A combined coaster and bottle opener 20 comprising a circular body provided with a side flange the edge of which is turned over

to form an opening lip, said body being provided with a fulcrum rib.

3. A combined coaster and bottle opener comprising a circular body provided with a 25 side flange the edge of which is turned over to form an opening lip, said body being provided with a fulcrum rib, and a center piece held in position by said rib.

4. A combined coaster and bottle opener 30 comprising a circular body provided with a side flange the edge of which is turned over to form an opening lip, said body being provided with a fulcrum rib having flanges, and a center piece secured in position by said 35 flanges.

In testimony whereof I affix my signature in presence of two witnesses.

EDMUND A. PARKER.
